M. W. RADKE.

WATER GAGE:

APPLICATION FILED MAY 25, 1918.

1,299,027.

Patented Apr. 1, 1919.

Inventor
Michael W. Radke

Watson E. Coleman
Attorney

UNITED STATES PATENT OFFICE.

MICHEAL W. RADKE, OF SAN BERNARDINO, CALIFORNIA.

WATER-GAGE.

1,299,027.

Specification of Letters Patent.

Patented Apr. 1, 1919.

Application filed May 25, 1918. Serial No. 236,619.

To all whom it may concern:

Be it known that I, MICHEAL W. RADKE, a citizen of the United States, residing at San Bernardino, in the county of San Bernardino and State of California, have invented certain new and useful Improvements in Water-Gages, of which the following is a specification, reference being had to the accompanying drawings.

10 This invention relates to certain improvements in water gages and has relation more particularly to a device of this general character including a transparent sight gage and it is an object of the invention to provide novel and improved means whereby the communications between the gage and the boiler may be cut off automatically upon breaking of the gage.

20 The invention consists in the details of construction and in the combination and arrangement of the several parts of my improved water gage whereby certain important advantages are attained and the device rendered simpler, less expensive and otherwise more convenient and advantageous for use, as will be hereinafter more fully set forth.

25 The novel features of my invention will hereinafter be definitely claimed.

30 In order that my invention may be the better understood, I will now proceed to describe the same with reference to the accompanying drawings, wherein:

35 Figure 1 is a view in side elevation of a water gage constructed in accordance with an embodiment of my invention; and

Fig. 2 is a view in front elevation with a portion of the device broken away as illustrated in Fig. 1.

40 As disclosed in the accompanying drawings G denotes a gage-column adapted to have its opposite ends in communication with a boiler in a conventional manner and said column is provided with the try-cocks

45 T of any desired type and preferably three in number. Also in communication with the gage-column G at points above and below the try-cocks T are the fittings F for the water-glass W. Carried by the fittings

50 F are the valves V of a conventional type for controlling the communication between the fittings F and the gage-column G.

The stems of the valves V have affixed thereto the gears 1 in mesh with the gears 2

55 rotatably supported by a frame A carried

by the gage-column G. Interposed between the last named gears 2 is a gear 3 which is rotated through the medium of the spring 4. The gear 3 constitutes a driving element and is normally held against movement through 60 the medium of the brake member M.

The brake member M comprises an elongated rod 5 pivotally engaged at a point intermediate its length with the frame A and said rod 5 is provided with a lateral extension 65 or finger 6 adapted to engage a tooth of the gear 3 for holding the same against movement under the influence of the spring 4. The end of the rod 5 adjacent the gear 3 is provided with a lateral extension 7 70 adapted to contact with the glass W whereby the extension or finger 6 is maintained in operative engagement with the gear 3. Secured to the frame A and to the end portion of the rod 5 remote from the extension 7 75 is a retractile member 8. Should the glass W break, the member 8 serves to swing the rod 5 in a direction to disengage the finger or extension 6 from the gear 3. The gear 3 then rotates under the influence of the spring 80 4 and this movement is transmitted through the gears 2 to the gears 1 and the direction of rotation of the gears 1 is such as to close the valves V. By this means it will be perceived that the escape of water or steam 85 upon breaking of the glass W is prevented.

I also find it of advantage to provide the shaft 9 of the gear 3 with an operating member 10 whereby the gears 1 may be rotated in a direction to adjust the valves V into open 90 position and at the same time place the spring 4 under tension.

From the foregoing description, it is thought to be obvious that a water gage constructed in accordance with my invention is 95 particularly well adapted for use by reason of the convenience and facility with which it may be assembled and operated and it will also be obvious that my invention is susceptible of some change and modification without 100 departing from the principles and spirit thereof and for this reason I do not wish to be understood as limiting myself to the precise arrangement and formation of the several parts herein shown in carrying out my 105 invention in practice except as hereinafter claimed.

I claim:

1. The combination of a gage-column, a water glass in communication therewith at 110

opposite ends and valves for controlling the communications between the water glass and the gage-columns; of a frame carried by the gage-column, a driving member supported by the frame between the valves and operatively connected therewith for closing the valves, a rod pivotally supported intermediate its length with the frame and having an end portion adapted to contact with the glass, said end portion being provided with a lateral extension engaging the driving member for holding said member against operation when the rod is in contact with the glass, and a spring secured to the opposite end portion of the rod and to the frame for disengaging the lateral extension of the rod from the driving member upon breaking of the glass to permit the driving member to close the valves.

2. In combination with a water glass and valves for controlling communication with the glass at opposite ends thereof, a driving member supported between the valves and operatively connected therewith for closing the valves, a rod supported for swinging movement and having one end portion in contact with the glass, said rod being provided with a lateral extension engaging the driving member for holding said member against operation when the rod is in contact with the glass, and automatic means for imparting swinging movement to the rod in a direction away from the driving member

to release the extension from said member upon breaking of the glass.

3. The combination of a gage-column, a water glass in communication therewith at opposite ends and valves for controlling the communications between the water glass and the gage-column; of a frame carried by the gage-column, a driving member supported by the frame between the valves and operatively connected therewith for closing the valves, a rod pivotally supported intermediate its length with the frame and having an end portion adapted to contact with the glass, said end portion being provided with a lateral extension engaging the driving member for holding said member against operation when the rod is in contact with the glass, and a spring secured to the opposite end portion of the rod and to the frame for disengaging the lateral extension of the rod from the driving member upon breaking of the glass to permit the driving member to close the valves.

In testimony whereof I hereunto affix my signature in the presence of two witnesses.

MICHEAL W. RADKE.
